(57) **CLAIM**

The ornamental design for an electric hair brush as shown and described.

DESCRIPTION

FIG. 1 is a front and top perspective view of an electric hair brush, showing my new design;

FIG. 2 is a front view thereof;

FIG. 3 is a rear view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is an enlarged view of portion 8 shown in FIG. 1; and, FIG. 9 is a front and top perspective view thereof, shown in an environment of use.

The dash-dash broken lines in the drawings illustrate portions of the article and form no part of the claimed design. Additional dash-dash broken lines illustrating a cover shown in FIG. 9 illustrate environmental subject matter and form no part of the claimed design. The dot-dash broken lines illustrate enlarged view indicators and form no part of the claimed design.

1 Claim, 9 Drawing Sheets(56)
